UNITED STATES PATENT OFFICE.

CARL RICHARD HIERONYMUS, OF NEW YORK, N. Y.

DESIGN FOR A FABRIC.

SPECIFICATION forming part of Design No. 13,542, dated January 23, 1883.

Application filed November 15, 1882. Term of patent 3½ years.

To all whom it may concern:

Be it known that I, CARL RICHARD HIERONYMUS, of New York city, county and State of New York, have invented a new and original Design for a Fabric, of which the following is a specification.

The accompanying drawing represents a face view of my new design.

This invention relates to a new ornamentation of woven fabric; and it consists in forming lines thereon, as hereinafter described.

a b c d represent four streaks or lines, parallel to each other and apparent on the face of the fabric. These four lines *a b c d* constitute 15 a group, A, by itself. There are series of such groups A A in the same line, with spaces inter-

vening, and there are series of rows of groups A A, as shown, alternating with which are series of groups B, each of which also consists of lines *a b c d*, as shown. The lines *a b c d* 20 are produced in the fabric in the form of depressions, elevations, or by colors.

I claim—

The design for a woven fabric, the same consisting of the groups A and B, each of said 25 groups being composed of lines *a b c d*, substantially as shown.

CARL RICHARD HIERONYMUS.
